UNITED STATES PATENT OFFICE.

ABRAHAM NOVICK, OF NEW YORK, N. Y., ASSIGNOR TO F. L. SMITH MACHINE COMPANY, INCORPORATED, OF NEW YORK, N. Y., A CORPORATION OF NEW YORK.

PROCESS AND MECHANISM FOR ATTACHING STRINGS TO ENVELOPES AND THE LIKE.

1,402,008.

Specification of Letters Patent.

Patented Jan. 3, 1922.

Application filed March 22, 1919. Serial No. 284,411.

To all whom it may concern:

Be it known that I, ABRAHAM Novick, a citizen of the United States, and a resident of New York, borough of Manhattan, in the county of New York and State of New York, have invented certain new and useful Improvements in Processes and Mechanisms for Attaching Strings to Envelopes and the like, of which the following is a specification.

- 10 This invention relates to processes and mechanisms for attaching string to envelopes and the like, and is particularly directed to means for attaching to the bodies or flaps, or both, of envelopes, one or more washers, 15 as by means of eyelets, and thereafter affixing a string to the body or flap portion of the envelope by winding that string between a washer and the envelope body or flap.
- 20 The object of my improvements is to provide means to these ends of greater efficiency and higher speed than is possessed by any mechanism known to me, and particularly to provide novel means for applying the 25 string by a novel method.

With these ends in view my improvements comprise features illustrated in the drawings accompanying this specification and showing the present preferred embodiment 30 of my improvements, wherein:

Figure 1 is a front elevation, partly in section on line 1—1 of Fig. 2, of so much of a washer and string attaching machine as suffices to show my improvements. Fig. 2 35 is a plan view corresponding with the showing of Fig. 1. Fig. 3 is a side elevation, partly in section, on line 3—3 of Fig. 2. Fig. 4 is a side elevation similar to that of Fig. 3, but showing a later step in the 40 operation of the mechanism. Fig. 5 is a fragmentary side elevation, partly in section, showing the final step in the operation of the mechanism. Fig. 6 is a front elevation of a fragment of the mechanism. Fig. 7 is a 45 fragmentary top plan view, partly in section, showing the winding of the string. Figs. 8 and 9 are a bottom plan view and sectional elevation, respectively, showing alternate means adapted to receive the string 50 winding. Figs. 1 to 6, inclusive, are to one scale, and Figs. 7 to 9, inclusive, are to another and larger scale.

My improved mechanism includes a pair

of oppositely disposed, axially aligned, coacting plungers or tool carriers, at least one of which is reciprocating, and which for convenience may be arranged with their common axis vertical. When one or both of said plungers are withdrawn from coacting relation, space is provided therebetween for the entrance to the field of coaction of said plungers, of the delivery ends of one or more washer supply devices and an eyelet supply device. As illustrative of one form of eyelet supply device and of washer supply device which are adapted for use with my improvements, I have shown the mechanisms employed for those purposes set forth in my Letters Patent of the United States No. 1,104,128, dated July 24, 1914, and for my present use I have shown two of such washer supply devices. This device is illustrated as particularly adapted for supplying round washers which have been previously formed and provided with a central hole therethrough and which are delivered from the bottom of a hopper by means of a reciprocating slide. It will be obvious, however, to those skilled in the art, that other shapes of washer are equally applicable and that other washer supplying devices may be equally efficient. For instance the device of Olm, set forth in Letters Patent of the United States No. 1,114,177, dated October 20, 1914, in which square or rectangular washers are cut from the leading end of an endless paper or fabric tape, would be equally efficient. Referring now to the drawings more in detail, 2 is the upper plunger carrying on its lower end eyelet setting die 4 and, surrounding that die, presser-ring 5. Said plunger may be reciprocated at suitable predetermined times by means not shown, connected with eye 6 at the upper end of said plunger. Said plunger is supported for endwise movement in bearing 7 fixed to some permanent framing not shown. Lower plunger 8 is mounted for rotation in sleeve 9 but is restrained against endwise movement relatively thereto by collar 10 thereon, which engages the upper end of said sleeve, and by pinion 12 and nut 11, the latter threaded onto the lower end of said plunger, the pinion engaging the lower end of said sleeve. At suitable predetermined times plunger 8 is rotated and to this end

pinion 12, fixed to said plunger, is engaged by gear 13 mounted for rotation on stud 14 supported in fixed part 15 of the framing. Sleeve 9 is supported for endwise movement 5 in fixed bearing 16, and such movement is imparted to said sleeve and plunger 8, carried thereby, through arm 17 fixed to rock-shaft 18 supported in fixed bearings in the framing not shown. The free end of said 10 arm 17 is bifurcated and engages pin 19 outstanding from sleeve 9. Shaft 18 is oscillated at predetermined times, by means not shown but which may be of known character, to cause plunger 8 at one time to rise 15 to the position of Fig. 4 and at another time to descend to the position of Fig. 5. The length of pinion 12 is sufficient to permit of said rising and descending while continuing in mesh with gear 13. Below gear 13 is con- 20 stantly rotating gear 80, and gear 13 is frictionally driven therefrom, one revolution at a time, said gear 13 being liberated for rotation by the withdrawal of latch 66 from engagement with lug 67 on said gear. Gear 25 13 is normally at rest, but when rotated at predetermined times by the clutch mechanism, is caused to make one complete rotation and stop. Said gear, being twice the diameter of pinion 12 meshing therewith, 30 will therefore cause said pinion to make two complete rotations and stop.

Reverting now to plunger 8, which is preferably of tubular construction, within the upper portion of the bore thereof is slidably 35 carried needle 21, and spring 22 is efficient for urging said needle upwardly in said plunger. The upper end of said plunger may be provided with seat 23 for the eyelet and with annular flange 24 within which the 40 paper washer is seated. Said flange is of a height in excess of the thickness of the washer for purposes which will appear later herein. Said flange is preferably beveled on the outside and said beveled wall is perfor- 45 at one point by passage 25 leading to channel 39 cut lengthwise in the interior wall of said plunger 8. This passage 25 and channel 39 is provided for the passage of the string upwardly through plunger 8. Sur- 50 rounding the upper end of plunger 8 and projecting a short distance thereabove is presser-sleeve 26 for coaction at predetermined times with presser-ring 5 on upper plunger 2. Said presser sleeve is mounted 55 for free rotation on said plunger and may be supported on ball-bearing 27 to that end. Between said ball-bearing and the lower end of the sleeve is spring 28, wrapped about plunger 8 for urging said sleeve upwardly. 60 The upward movement of said sleeve is limited by pin 29 thereof in engagement with groove 30 around plunger 8.

Contiguous to plunger 8 and adjacent its upper end when that end is in its lowermost 65 position of Fig. 5, is the string cutting mech-

anism. This mechanism comprises fixed blade 31 supported from bearing 16, and movable blade 32 pivoted at 33 to the fixed blade. Said movable blade may be oscillated relatively to fixed blade 31 at suitable times 70 to sever the string therebetween by the following means: Handle 34 is adjustably mounted in slide bar 35 and said slide bar is pivoted at that end thereof opposite handle 34, to one arm of bell-crank 36 pivoted at 75 37 in a fixed part of the framing. The other end of said bell-crank is pivoted to one end of link 38 the other end of which is pivoted to movable blade 32.

Directing attention now to the washer and eyelet supply, vertical stack 41 of circular paper or cardboard washers, each having a central hole therethrough, may be supported on rod 42 held in bracket 43 outstanding from bearing 7 of plunger 2. Mounted for reciprocation transversely of said stack and across the bottom thereof is washer-slide 44. The leading end of said slide is efficient to scrape off from the bottom of said stack a washer and advance that washer to coaxial relation with plungers 2 and 8. For causing the reciprocation of said slide, bell-crank lever 45 is pivoted at 46 to a fixed part of the framing, one arm of said bell-crank being bifurcated for engagement with pin 47 fixed 90 to said slide, and the other arm pivotally connected to link 48, which is actuated at predetermined times, by means not shown, for causing said slide to reciprocate as described. 100

Similar stack 49, washer slide 50 and bell-crank 51, are provided to supply a second washer below the plane of delivery of said first washer. For convenience these washer supply devices are arranged in angular relation back of the transverse central plane 1, 1 of Fig. 2, and preferably midway between them is located the eyelet supply. Said eyelet supply may comprise hopper 52 pivoted at 53 in bracket 54 outstanding from bearing 7. Depending from said hopper is eyelet chute 55 whose delivery nose 56 is adapted to be oscillated about pivot 53, into and out of engaging relation with plungers 2 and 8. Said eyelet hopper and chute may be oscillated the required distance and at predetermined times by means of link 57 pivotally connected to arm 58 of said hopper. 110

In many cases it is desirable to set a washer and eyelet on the body of the envelope at the same time that the flap equipment is being provided. To this end anvil arm 59 is provided, outstanding from bearing 7 preferably directly opposite eyelet hopper 52. For coaction with anvil 60 on said arm, plunger 61 having spring supported needle 62 therein, is provided. Said plunger may be reciprocated a suitable distance at predetermined times in fixed bearing 63 by means not shown. The usual eyelet supply 64 and 130

washer supply 65 may also be provided, adapted and actuated for supplying eyelets and washers respectively at predetermined times.

5 It will be understood that, while plunger 2 is illustrated as reciprocating, such reciprocation, while desirable, is not essential to the successful operation of the mechanism. Die 4 thereof could very well be permanently located closer to and just above the inner position of the leading end of washer slide 44. Or, if only one washer is applied (from slide 50), said die 4 could be permanently located even lower and closer to the position of the 10 envelope flap 70, Fig. 1. In either of these arrangements plunger 8 would rise to meet said die.

It will also be understood that, while I have chosen to illustrate my improvements 20 in connection with a washer attached by means of an eyelet to a sheet of material, my invention is equally efficient for winding a string about any member attached to a sheet of material and capable of retaining the 25 string thus wound.

For instance, said washer may be in the form of the common metal paper fastener having a head, round or of other shape, and two or more prongs bent over onto the opposite face of the sheet of material and the string may be wound either about the head or prongs. See Figs. 8 and 9.

The operation of my improved mechanism is as follows: Eyelet hoppers 52 and 68 being supplied with eyelets and washers 41 being stacked on their respective rods, as 42 of stack 41, an envelope is introduced to the machine with its flap 70 in position over needle 21 and with its back portion 69 over 40 anvil 60 on arm 59, with the mechanism in position just prior to that shown in Fig. 3. The several elements of the mechanism are then advanced to the positions shown in Figs. 1, 2 and 3, wherein the slides 44 and 45 50 have each delivered a washer into line with needle 21, and chute 55 has delivered an eyelet into similar relation. Also slide 71 has delivered a washer, and chute 72 has delivered an eyelet, into engaging position 50 with needle 62. Also needle 21 has risen with sleeve 9 and passed through the eyelet, the lower washer, the envelope flap and the upper washer, and is in engagement with die 4 in plunger 2. Also needle 62 has 55 passed through the eyelet delivered by chute 72, the washer delivered by slide 71 and the back 69 of the envelope body. The several washer slides and eyelet chutes then withdraw, as shown in Fig. 4, plunger 2 descends, sleeve 9 continues its upward movement, needle 21 being forced downwardly in plunger 8 by anvil 4, and the eyelet is upset against said anvil, thereby securing the two washers on opposite sides respectively of the envelope flap. At the same

time plunger 61 descends and the eyelet is upset against anvil 60, thereby securing the washer to back portion 69.

The foregoing operations are all known in the art and are preparatory to the following steps which embody the essential features of my improvements: As plungers 2 and 8 meet for setting the eyelet on the envelope flap, presser-ring 5 and presser-sleeve 26 engage the envelope flap on opposite faces, respectively, presser-ring 26 yielding slightly downwardly against the pressure of spring 28. As the transverse plane of engagement of said ring 5 and sleeve 26 is higher than the plane of engagement of the eyelet setting members, the envelope flap is crowded upwardly, Fig. 4, away from the edge of the lower washer, thereby providing an opening between that washer and the flap for the free entrance 85 of string 73 therebetween. It will be understood that said string has previously been led upwardly in channel 39 of plunger 8 and out of the top of said plunger through angularly disposed passage 25, and that the 90 free end of said string hangs over the outer edge of presser-ring 26. Said string is retained in position by spring 74.

The mechanism is now in position for winding the string between said flap and 95 lower washer. This is accomplished by liberating clutch latch 66 from engagement with lug 67 of gear 13, and which gear thereupon makes one complete revolution, when its lug 67 is again engaged by latch 100 66, bringing that gear to rest. This rotation of gear 13 causes pinion 12 and plunger 8 to make two complete revolutions whereby string 73 is wound twice about the eyelet as an axis, between the flap and the lower 105 washer. The outer end of the string being gripped between the flanges respectively of ring 5 and sleeve 26, against the envelope flap, a sufficient portion of string for winding between said washer and flap is drawn 110 under tension of spring 74 from that portion of the string within channel 39 of plunger 8. Annular flange 24, on the upper end of plunger 8, is efficient to cause the string, when being wound, to always pass above 115 the washer, as the upper edge of that flange stands above the upper face of the washer. During the rotation of plunger 8, ring 26 will be held against rotation by its frictional engagement with flap 70 which in turn 120 is supported by ring 5. The rotation of plunger 8 will wind the string in clockwise direction and dispose it as shown in Fig. 7. Plungers 2 and 8 then separate, the lower one retracting to the position of Fig. 5, adjacent the cutting mechanism. The operator will then lift the flap off needle 21 and move the envelope to the left, Fig. 3, thereby withdrawing portion 69 from arm 59. String 73 will thereby be drawn be- 130

5   tween blades 31 and 32 and presently the hand of the operator, in which is gripped the envelope, will collide with handle 34, moving that handle to the left, Fig. 3, and toward the bottom, Fig. 2, thereby causing the shears to coact and sever the string, leaving a short length protruding from passage 25. The operation is thereby completed, and the machine is ready for the 10 reception of another envelope and the repetition of the described operation.

I claim:

1. The combination of means for attaching a portion of a washer to a sheet of material, and means for winding a string between the washer and the sheet of material.

2. The combination of means for separating the outer edge of a washer from a sheet 20 of material to which a portion of the washer has been previously attached, and means for winding a string between the washer and the sheet of material.

3. The combination of means for attaching 25 a portion of a washer to a sheet of material, means for separating the outer edge of the washer and the sheet of material, and means for winding a string between the washer and the sheet of material.

4. In mechanism for winding a string between a washer attached to a sheet of material and said sheet of material, the combination of a plunger adapted and actuated for reciprocation and rotation, means for locating 35 said sheet and washer relatively to said plunger, a string passage lengthwise said plunger having its delivery end adjacent the periphery of the washer, and means for flexing said sheet to provide space for the entrance of the string between said washer and sheet and for gripping the end of the string.

5. The combination of means for bringing 45 into coacting relation opposite instrumentalities for setting an eyelet for securing together a previously associated eyelet washer and sheet of material, means carried by one of said instrumentalities for presenting adjacent the periphery of the washer the end of a string, means for gripping said end of string, and means carried by the string presenting instrumentality and operative after the setting of the eyelet for winding the body of said string between 50 said washer and sheet of material.

6. The combination of means for bringing 60 into coacting relation opposite coaxial instrumentalities for setting an eyelet for securing together a previously associated eyelet, washer and sheet of material, means carried by one of said instrumentalities for presenting adjacent the periphery of the washer the end of a string, means carried by said opposite instrumentalities, respectively, for separating the periphery of said

washer and sheet of material, and for gripping said end of string, and means for rotating the string presenting means and operative after the setting of the eyelet for winding the body of said string between the 70 washer and the sheet of material.

7. The combination of means for bringing into coacting relation opposite coaxial instrumentalities for setting an eyelet for securing together a previously associated eyelet, washer and sheet of material, means carried by one of said instrumentalities for presenting adjacent the periphery of the washer the end of a string, means carried by said opposite instrumentalities, respectively, for separating the periphery of said washer and sheet of material, and for gripping said end of string, means for rotating the string presenting means and operative after the setting of the eyelet for 80 winding the body of said string between the washer and the sheet of material, and means for severing a predetermined length of string.

8. In mechanism for attaching a washer 90 and a string to a sheet of material the combination of oppositely arranged coacting eyelet setting means, one of said means comprising a reciprocating plunger, a needle carried thereby and yieldable in the direction of reciprocation of said plunger, means for delivering a washer and means for delivering an eyelet into the path of reciprocation of said needle, means carried by said plunger for delivering the end of a string 95 adjacent the periphery of said washer, means for gripping said end of string, and means operative after the setting of the eyelet for 100 rotating said plunger for winding the body of said string between said washer and sheet 105 of material.

9. In mechanism for attaching a washer and a string to a sheet of material the combination of oppositely arranged coacting eyelet setting means, one of said means comprising a reciprocating plunger, a needle carried thereby and yieldable in the direction of reciprocation of said plunger, means for delivering a washer and means for delivering an eyelet into the path of reciprocation of said needle, means carried by said plunger for delivering the end of a string adjacent the periphery of said washer, means for gripping said end of string, means operative after the setting of the eyelet for 110 rotating said plunger for winding the body of said string between said washer and sheet 115 of material, and means for severing a predetermined length of string.

10. In mechanism for attaching a washer 120 and a string to a sheet of material, the combination of oppositely arranged coacting eyelet setting means, one of said means comprising a reciprocating plunger, a needle carried by said plunger and yieldable in 125

- the direction of reciprocation thereof, means for delivering a washer and means for delivering an eyelet into the path of reciprocation of said needle, means carried by 5 said plunger for delivering the end of a string adjacent the periphery of said washer, means carried by said opposite instrumentalities, respectively for separating the periphery of said washer and sheet of material, and for gripping said end of string, and means for rotating the string presenting means for winding the body of the string between the washer and the sheet of material. 10
- 15 11. In mechanism for winding a string between a washer attached to a sheet of material and said sheet of material, the combination of a plunger adapted and actuated for reciprocation and rotation, means for locating said sheet and washer relatively to said plunger, a seat for the washer in the operative end of said plunger, a string passage lengthwise said plunger having its delivery end adjacent the periphery of the 20 washer seat, a presser-sleeve mounted for free rotation about the operative end of said plunger, said presser-sleeve being yieldable lengthwise said plunger and having its operative face extending beyond the end of 25 said plunger, and a presser-ring opposite said presser-sleeve for coaction therewith.
12. In mechanism for winding a string between a washer attached to a sheet of material and said sheet of material, the combination of a plunger adapted and actuated for reciprocation and rotation, means carried by the operative end of said plunger for locating said sheet and washer relatively to said plunger, a die for coaction 30 with said locating means, a seat for the washer in the operative end of said plunger, 35 an annular flange on said plunger end surrounding said washer seat, a string passage lengthwise said plunger having its delivery end radially beyond the upper edge of said annular flange, a presser-sleeve mounted for free rotation about the operative end of said plunger, said presser-sleeve being yieldable lengthwise said plunger, and a presser-ring carried by said die for coaction with the presser-sleeve. 45
13. That improvement in the art of attaching a string to a sheet of material comprised in providing said sheet with a member attached to said sheet by a portion thereof and winding the string between said member and said sheet. 50
14. That improvement in the art of attaching a string to a sheet of material comprised in providing said sheet with a member attached to said sheet by its midportion and winding the string between said member and said sheet. 55
15. That improvement in the art of attaching a string to a sheet of material comprised in attaching a washer by a portion thereof to said sheet of material and then winding the string between the unattached portions of said washer and the sheet of material. 60
16. That improvement in the art of attaching a string to a sheet of material comprised in placing a washer on said sheet, securing said washer and sheet together by means of an eyelet smaller than the washer, and then winding the string between that portion of the washer protruding beyond the eyelet and the sheet of material. 65
- In witness whereof, I hereby affix my signature this 20th day of March, 1919.
- ABRAHAM NOVICK.
